UNITED STATES PATENT OFFICE.

HENRY E. BANDLOW, OF CHICAGO, ILLINOIS, ASSIGNOR TO NATIONAL STAMPING & ELECTRIC WORKS, OF CHICAGO, ILLINOIS, A CORPORATION OF ILLINOIS.

LANTERN.

1,257,175.

Specification of Letters Patent. Patented Feb. 19, 1918.

Application filed March 29, 1917. Serial No. 158,207.

To all whom it may concern:

Be it known that I, HENRY E. BANDLOW, a citizen of the United States, and a resident of Chicago, in the county of Cook and State 5 of Illinois, have invented certain new and useful Improvements in Lanterns; and I do hereby declare that the following is a full, clear, and exact description thereof, reference being had to the accompanying drawings, and to the characters of reference 10 marked thereon, which form a part of this specification.

This invention relates to improvements in lighting fixtures, and refers more especially 15 to an improved lantern of that type whose source of light is derived from a hydrocarbon liquid under pressure, such as gasolene, and the invention consists in the combination and arrangement of the parts shown in 20 the drawings and described in the specification, and is pointed out in the appended claims.

The present improvements refer more specifically to that type of lantern or light 25 fixture wherein an inverted burner, equipped with a refractory mantle is employed to increase the candle power of the light, and is directed to means for suitably cooling the parts of the lantern structure beneath the 30 mantle so as to prevent the lantern becoming excessively hot, especially in the event that the mantle should be broken and the flame be directed against the subjacent lantern structure.

35 I have shown in the drawings an approved form of construction which has demonstrated its practicability in use but it will be understood that the invention is capable of some variation within the spirit and scope of the 40 claims hereto appended.

In the drawings:—

Figure 1 is a dotted outline of a standard lantern, showing in full lines my invention applied thereto.

45 Fig. 2 is a perspective view of the deflector plate or disk and cooling tube.

Fig. 3 is a plan view of the deflector plate or disk.

As shown in the drawing, 10 designates 50 the reservoir of the lantern on which is supported the frame or cage 11, through the medium of a hollow neck 12, that is perforated to permit air to pass into the lantern structure and upwardly through perforations in

the bottom plate 14 of the burner chamber. 55 Said lamp frame may be made of any usual or preferred construction, and in the type of lantern herein shown it is arranged to support a transparent cylindric shield or globe, preferably made of mica. 15 designates the 60 fuel pipe upwardly through which fuel from the reservoir is carried to a mixing or carbureting chamber 16 that is supplied with air to produce a combustible mixture through a pipe 17 that extends downwardly therefrom and through the bottom plate of the 65 burner chamber. A goose neck pipe 18 conducts the burning mixture to a depending or inverted burner 19 which is shaped to receive an inverted mantle 20.

70 These features of construction constitute, in themselves, no part of the present invention and may be variously constructed.

In addition to the perforations in the bottom plate 14 of the burner chamber, through 75 which cooling air is admitted to the interior of the burner chamber, there is provided a centrally located cool air delivery pipe 22 which is anchored in any suitable manner in the top wall of the reservoir. Said pipe is 80 closed at a lower end and is provided near its lower end with one or more openings 23, of ample area to admit a draft of cooling air to the pipe. The pipe extends upwardly through the bottom plate 14 of the burner 85 chamber and is screw threaded at its upper end to receive upper and lower clamping nuts 24, 25 between which said bottom plate of the burner chamber is confined, and by 90 which the parts are united rigidly together. The said cool air pipe 22 is located centrally beneath the mantle and burner so as to direct a column of cool air into that part of the 95 burner chamber which is in the direct influence of the burner flame. Said pipe is provided to maintain the parts suitably cool and to prevent the flame overheating the metallic lower plate of the burner chamber and the neck 12 to such extent as to excessively and dangerously raise the temperature of the top 100 wall of the metal reservoir 10, especially when the mantle is broken, at which time the heat is thrown more directly against the bottom wall of the burner chamber than when the mantle is intact.

105 As a means to further avoid the concentration or localization of heat against the central portion of the lantern structure when

the mantle is broken, there is provided a deflecting plate or shield 27 which is located centrally over the mouth of the cool air pipe 22 and beneath the burner and is made of 5 considerable diameter with respect to the diameter of the air pipe. Said disk may be attached to the lantern structure in any suitable or preferred way that will hold it in place. As herein shown, and preferably, it 10 is clamped in place by the upper clamping nut screw threaded to the cool air pipe as aforesaid; said disk being provided with a down turned member 28 which terminates in a horizontal apertured arm 29 that lies over 15 the said plate and through which said cool air pipe extends. Said arm is clamped between said plate and the upper nut 25 of said pipe.

The said disk is in the direct path of the 20 incoming cool air from the pipe 22, so that the rising column of cool air tends to cool the disk. Moreover the disk, being spaced from the bottom plate of the burner chamber, circulation of cool air is permitted between 25 said disk and bottom plate, thereby further reducing liability of the plate, or the cool air pipe itself, becoming unduly heated, so as to transmit heat to the reservoir below.

30 Furthermore the disk or shield, being located in the direct path of the burner flame, in the event of a breakage of the mantle, it has the effect of diverting the heat of the flame or spreading it outwardly so as to 35 meet the incoming cool air from the cool air pipe, which is itself diverted or spread outwardly by its impingement against the lower face of the disk, so that thereby the cool air is applied in an efficient manner 40 to prevent localized heating of the lantern structure. The air which passes into the lantern chamber rises as its temperature is elevated through the chamber and passes outwardly therefrom through the perforated top portion of the lantern beneath the 45 dome.

I claim as my invention:—

1. A light fixture having an inverted burner and a burner chamber having a perforated bottom wall, combined with a fuel reservoir below the chamber, communicating with the burner, and a cool air pipe arranged centrally of said burner and chamber and extending upwardly from said 50 reservoir through said bottom wall to deliver cool air to said chamber.

2. A light fixture having an inverted burner and a burner chamber having a bottom wall, combined with a fuel reservoir 55 below the burner and chamber, communicating with the burner, a cool air pipe extending through said bottom wall and arranged centrally of the burner above the reservoir to deliver air to said chamber, and a deflecting shield between the mouth of said pipe

and the burner and spaced a distance from the mouth of said pipe.

3. In a gasoline lantern, a reservoir, a burner chamber thereabove, an inverted burner centrally within said chamber and communicating with the reservoir and with the atmosphere, said chamber being provided with a bottom wall, and a cool air pipe extending centrally upwardly through the bottom wall beneath the burner and anchored to the reservoir. 75

4. In a gasoline lantern, a reservoir, a burner chamber thereabove, an inverted burner centrally within the chamber and communicating with the reservoir and with the atmosphere, said chamber being provided with a bottom wall, a cool air pipe extending centrally upwardly through said bottom wall beneath said burner and anchored to the reservoir, said pipe being 85 screw threaded at its upper end and nuts threaded to said upper end of the pipe between which the bottom wall of the burner chamber is confined.

5. In a gasoline lantern, a reservoir, a burner chamber thereabove, an inverted burner centrally within the chamber and communicating with the reservoir and with the atmosphere, said chamber being provided with a bottom wall, a cool air pipe extending centrally upwardly through said bottom wall beneath said burner and anchored to the reservoir, said pipe being screw threaded at its upper end, nuts threaded to said upper end of the pipe between 95 which the bottom wall of the burner chamber is confined, and a deflecting plate or shield located above the bottom wall and centrally over the outlet end of the cool air pipe. 100

6. In a gasoline lantern, a reservoir, a burner chamber thereabove, an inverted burner centrally within the chamber and communicating with the reservoir and with the atmosphere, said chamber provided with a bottom wall, a cool air pipe extending upwardly centrally through the bottom wall of the chamber beneath the burner and anchored to the reservoir, and a deflecting plate arranged between the outlet end of 115 the cool air pipe and the burner and spaced from said pipe, with means for supporting said plate on said pipe. 110

7. In a gasoline lantern, a reservoir, a burner chamber thereabove, an inverted burner centrally within the chamber and communicating with the reservoir and with the atmosphere, said chamber being provided with a bottom wall, a cool air pipe extending centrally upwardly through said 120 bottom wall beneath the burner and anchored to the reservoir, a deflecting plate arranged between the outlet end of the cool air pipe and the burner and spaced from said pipe, said plate being provided with a 130

downturned member which terminates in a horizontal apertured attaching member and the upper end of the cool air pipe extending through the apertured attaching member and a nut screw threaded to the said upper end of the cool air pipe to fix the deflector plate member thereto.

8. In a lantern, a deflecting shield provided with a downturned member terminating in an apertured attaching arm, combined with a cool air tube extending through

said attaching arm, with means to fix said attaching arm to said tube.

In testimony whereof I claim the foregoing as my invention, I hereunto append my signature in the presence of two witnesses at Chicago, Illinois, this 24th day of March, 1917.

HENRY E. BANDLOW.
